WHIP ROLL FOR LOOMS.

Application filed August 4, 1927. Serial No. 210,655.

This invention relates to improvements in whip rolls for looms and it is the general object of the invention to provide a whip roll having a yielding surface to ease the strains which temporarily occur on certain of the warp threads.

In the normal operation of a loom the harness motion is likely to keep the warp threads in a state of almost constant movement in order to form successive sheds. This results in placing the warp threads under strains which increase as the harnesses reach the extreme limit of their movement and it is found in certain classes of goods that the breakage of the warp threads is the factor which determines the number of looms which can be operated by a weaver. In winding the warp threads on the beam it occasionally happens that certain of the threads will be placed under a temporary excess strain and as the beam turns in the loom these strained warp threads will be paid off at a less rate than those which are under normal strain, with the result that the strained threads are likely to break. The whip rolls which are ordinarily employed have a yielding motion, but they do not yield unless the greater part of the warp threads are subject to a strain. It is found that the whip rolls even of the more sensitive type will not yield if a very small number of warp threads are under heavy strain.

It is an important object of my present invention to provide a whip roll with a yielding surface such as rubber so that the threads which are temporarily under excessive strain may be embedded somewhat in the surface of the whip roll to relieve the stress. The surface of such a whip roll will be deformed depending upon local requirements. The whip roll may be mounted for yielding movement as a whole so that the same can yield should a shuttle be caught in the shed and thus prevent breakage of a large number of warp ends.

With these and other objects in view which will appear as the description proceeds, my invention resides in the combination and arrangement of parts hereinafter described and set forth in the claims.

In the accompanying drawings wherein two forms of my invention are shown,

Fig. 1 is a sectional side elevation of a

loom having the preferred form of my invention applied thereto,

Fig. 2 is a top plan view of a portion of the preferred form of whip roll taken in the direction of arrow 2, Fig. 1, on an enlarged scale,

Fig. 3 is a vertical cross section on line 3-3 of Fig. 2,

Fig. 4 is a view similar to a portion of Fig. 1 but showing a modified form of the invention, and

Fig. 5 is a fragmentary rear elevation view taken in the direction of arrow 5, Fig. 4.

Referring to Fig. 1 it will be seen that I have provided a loom frame 10 at the rear of which is supported a warp beam 11. Harnesses 12 control the warp W while the cloth C extends over the breast beam 13 and is led downwardly to the take up roll 14. During the weaving of the cloth the beam 11 rotates to let off warp and the roll 14 takes up the cloth as it is woven, the harness frames producing the required sheds. The matter thus far described is common and forms no part of my present invention.

As previously stated it not infrequently happens that a temporary tension on one or more of the warp threads coming from the beam 11 will set up stresses which result in breakage of the warp threads. The forms of whip roll heretofore used have yielded sufficiently to prevent the breakage of threads when a comparatively large number are under excess tension, but they have not been sensitive enough to yield when one thread is unduly stressed. In order to permit any thread which may be under more strain than its neighbors to follow a somewhat shorter path than usual I provide a whip roll, the preferred form of which is shown in Figs. 1, 2 and 3, as comprising a core 20 around which lies a body of india rubber or rubbery material indicated at 21. The material 21 is soft and will yield at any point throughout the length of the whip roll to lessen the strain of any warp thread which may be under unusual stress.

As shown in Fig. 2 I have indicated at S several points of stress and have shown how the resilient surface of the roll will yield at these points to prevent breakage of the warp threads. It is highly desirable of

course that the portion of the roll which is engaged by the warp threads shall have a continuous surface throughout its length as well as to be readily yieldable and these qualities are possessed by india rubber, although any other flaccid material which will yield at any desired point along the length of the whip roll without requiring a corresponding yielding of other points 10 where the warp is under normal strain will answer the purpose. I find that it is not always the same thread which breaks but that the breakage is distributed throughout the warp, indicating that warp faults are 15 not due to any one thread being shorter than the others throughout the whole length of the warp but rather to the fact that many of the threads are placed under temporary strains when a certain part of the warp is 20 being unwound, these strains being relieved and others set up as the warp beam rotates. For this reason the deformed portions of the whip roll indicated at S will not always be in the same place.

25 Forward yielding movement of the form of roll set forth in Figs. 1, 2 and 3 is provided for by passing the gudgeon 30 on each end of the roll through a head 31 carried by a rod 32. The rods each slide in a bracket 33 and are urged rearwardly by springs 34, the purpose of this mounting being to permit the whip roll as a whole to move forwardly should the entire warp or any large portion thereof be placed under temporary excessive strain.

30 In the whip roll heretofore described the material 21 is held tightly to the core 20 but under certain conditions such a roll may not be desirable and in order to provide a construction wherein the yarn engaging flexible element may be removable and renewable I use the modified form shown in Figs. 4 and 5. As shown therein the whip roll 40 may correspond to the usual form of steel roll 45 but it will be provided at each end thereof with a flange 41, one of which is shown in Fig. 5. Between the flanges and supported by the roll is located a loose band of such material as india rubber indicated at 42, the 50 internal diameter of the band being in excess of the diameter of the whip roll 40. By this construction the band 42 will creep around the roll 40 and will act to absorb temporary strains as is the case with the preferred form of the invention. While I have shown the flanges 41 for the purpose of restraining improper endwise movement of the band 42 yet I do not wish to be limited to this particular means for holding said 55 band in proper alignment with the warp threads. It is obvious from the modified form that the same may be turned inside out to present a new surface to the warp.

60 From the foregoing it will be seen that I have provided a whip roll presenting to the

warp a surface which can yield at any point throughout the width of the warp to accommodate temporary strains and that the surface in contact with the warp threads is continuous throughout the width of the warp 70 irrespective of the location or number of deformations therein. It will further be seen from the modified form of the invention that I have provided an endless band which is loosely mounted on a whip roll and 75 capable of creeping movement thereover, said band acting to relieve occasional stresses in the warp and so formed that it may be turned inside out to present a new surface to the warp. While I have specified india 80 rubber as the material to be used both in the preferred and modified forms of the invention, yet as previously stated any inherently resilient flaccid material which is capable of deformation at a number of spaced 85 points without causing deformation of the entire length of the whip roll will suffice.

Having thus described my invention it will be apparent that changes and modifications may be made therein by those skilled 90 in the art without departing from the spirit and scope of the invention, and I do not wish to be limited to the details herein disclosed but what I claim is:

1. A loom whip roll having a yarn engaging surface of soft india rubber.
2. A loom whip roll having a yarn engaging surface of a material composed of soft rubber and which is elastically yieldable to a single thread.
3. A loom whip roll having a yarn engaging surface of soft rubber capable of yielding at any point throughout its length.
4. A loom whip roll having a yarn engaging surface formed of material which is elastically yieldable to a single thread at any point throughout the length of the roll independently of the remainder of the roll.
5. In a loom having a supply of warp, a whip roll over which the warp extends, and a soft rubber surface on the whip roll to absorb slight temporary excess tension on individual warp threads while the whip roll as a whole remains at rest.
6. In a loom, a warp beam, harness frames, take-up mechanism, said beam, harness frames and take-up mechanism acting during the normal operation of the loom to place the warp threads under a normal tension, and a whip roll having a yarn engaging surface of soft rubber capable while remaining at rest of relieving temporary excess tension in any warp thread.
7. A loom whip roll having a rotatable yarn engaging surface of soft india rubber.
8. In a warp controlling mechanism for a loom, a warp beam, harness mechanism for the warp and a device between the warp beam and the harness mechanism in con-

tact with the warp to guide the latter, said device having a surface formed of elastic material which may be deformed at any point independently of the adjacent point, 5 said surface being yieldable under excess strain to prevent breakage of a single thread which may be temporarily placed under abnormal strain.

9. In a loom having a supply of warp, 10 a whip roll having a rigid body, and a band of soft rubber loosely mounted on the whip roll and rotatable about the latter as the warp is fed through the loom.

10. In a loom having a supply of warp, 15 a whip roll having a rigid body portion, and a band of elastic material yieldable to

a single thread, said band being loosely supported on and rotatable around the body portion of the whip roll.

11. In a loom having a supply warp, a 20 whip roll having a substantially rigid body portion, flanges on the ends of the whip roll, and a band of material which is elastically yieldable to a single thread loosely mounted on the body portion of the roll 25 and rotatable about the latter and limited as to endwise motion relatively to the whip roll by said flanges.

In testimony whereof I have hereunto affixed my signature.

RICHARD GREENLEAF TURNER.
